UNITED STATES PATENT OFFICE.

CHARLES VAN DYECK, OF NASHVILLE, TENNESSEE.

IMPROVEMENT IN SPRING-MATTRESSES.

Specification forming part of Letters Patent No. 57,223, dated August 14, 1866.

To all whom it may concern:

Be it known that I, CHARLES VAN DYECK, of Nashville, in the county of Davidson and State of Tennessee, have invented a new and useful Improvement in Spring-Mattresses; and I do hereby declare that the following is a full, clear, and exact description of the same, reference being had to the annexed drawings, made part of this specification, in which—

Figure 1 is a vertical longitudinal section. Fig. 2 is a top view; and Fig. 3 is a plan, showing the construction of the diaphragm.

The same letters refer to identical parts.

A is a staunch frame, of iron or other suitable material, across which is spread the spring-linen b, made of suitable material. a a are spiral springs, tapering from both ends toward the middle. These springs are passed through the spring-linen b to their middle, being sustained by the fabric through which they

pass, and secured in a vertical position by a net-work of cords, c, extending from the frame, and knotted or otherwise attached to the outer coil of the spiral springs, as shown in Fig. 3.

The frame and springs thus constructed are inclosed in a casing of ticking, d, suitably padded to protect the springs.

What I claim as my invention, and desire to secure by Letters Patent, is—

A spring-mattress constructed with a frame, A, diaphragm b, and spiral springs a a, inclosed in a casing, d, the several parts being constructed, secured, and arranged for use substantially as set forth.

CHARLES VAN DYECK.
